UNITED STATES PATENT OFFICE.

GIRARD CARL ROBINSON, OF DETROIT, MICHIGAN.

ADJUSTABLE-POINT LATHE-CENTER.

1,317,894.

Specification of Letters Patent.

Patented Oct. 7, 1919.

Application filed March 27, 1919. Serial No. 285,691.

To all whom it may concern:

Be it known that I, GIRARD C. ROBINSON, a citizen of the United States, residing at Detroit, in the county of Wayne and State 5 of Michigan, have invented new and useful Improvements in Adjustable-Point Lathe-Centers, of which the following is a specification.

This invention relates to lathe centers, and 10 more specifically to an improved construction in which the center-point is adjustable longitudinally within the center-point holder.

One object of this invention is to provide 15 an improved adjustable center for lathes, grinders or other machines, which renders it unnecessary to move the tail-stock when changing center-pins or center-points.

Another object is to provide an improved 20 device of this character which accomplishes a great saving of time and material in the operation of re-grinding or re-pointing the center-point.

Other objects and advantages may become 25 apparent to persons who read the following details of description in connection with the accompanying drawings, in which:

Figure 1 is a side elevation of a center-point holder and its adjuncts constructed 30 and assembled in accordance with the present invention.

Fig. 2 is a perspective view of the center-pin or center-point, detached.

Fig. 3 is a rear end view of the complete 35 device shown in Fig. 1.

Fig. 4 is a transverse sectional view along the line 4-4 of Fig. 1.

Referring to these drawings in detail in which similar reference characters correspond 40 with similar parts throughout the several views, the invention comprises a tubular body or center-point holder 5, a center-pin or center-point 6, a screw or adjuster 7 and a set-screw 8.

The body 5 is hollow throughout its length, the intermediate portion of the hollow being 45 screw-threaded for meshing with the screw or adjuster 7, the rear portion of the hollow being enlarged, as indicated at 10, to protect the screw from mutilation and the front end of the hollow being cylindrical so as to conform 50 to the convex surface of the center-pin 6. The center-point holder 5 is provided with a radial aperture 11 which receives the 55 set-screw 8, and this aperture 11 is in open communication with the center-pin seat

which is formed by the front portion of the hollow or bore through the center-pin holder 5. The set-screw 8, therefore, may be turned and thereby caused to exert a pressure against a slabbed surface 12 of the pin 6 so as to secure the latter against turning in the body 5. The slabbed surface is not essentially plane as shown, but may consist of any cut-away or slabbed surface which breaks the cylindrical surface and coacts with the set-screw for preventing the center-point from turning.

The screw 7 is operable by any appropriate means, so as to adjust the center-pin 7 by pushing it forward to the desired position, and the set-screw 8 co-acts with the screw 7 to hold the center-point rigid with relation to the center-point holder.

The body 5 is preferably carbonized and hardened steel and is tapered rearwardly from a portion adjacent to its front end, the taper of this portion corresponding to that of the longitudinal bore of a standard tail-stock-spindle, although this taper may be 81 varied by the manufacturer when desirable.

The center-point is preferably made of high-speed steel and therefore, it is not required that another point be substituted therefor until it has undergone a large amount of hard and constant uses. However, when it is necessary or desirable to remove the center-point 6, the set-screw 8 may be loosened to permit the center-point to be withdrawn from its seat.

What I claim as my invention is:

1. The combination of a center-point holder, a center-point longitudinally adjustable therein, adjusting means in the center-point holder for effecting the longitudinal adjustment of the center-point, and clamping means to coact with said adjusting means to secure said center-point in rigid relation to said center-point holder in the different adjustments of the center-point.

2. The combination of a center-point holder, a center-point longitudinally adjustable therein, and having a slabbed surface extending therealong, means in the center-point holder for adjusting the center-point, and a set screw operable in said center-point holder and settable against said slabbed surface to prevent rotation of the center-point and to coact with said means in preventing accidental longitudinal movement of the center-point.

3. The combination of a center-point

holder having a bore extending longitudinally therethrough, a center-point having a slabbed side, a screw threaded adjuster, and a set screw, the forward end of said longitudinal bore constituting a seat for said center-point, a part of said bore behind said seat being screw-threaded and meshing with

the threads of said adjuster, said center-point holder having a radial bore which is screw-threaded and in which said set-screw ¹⁰ operates to bear against said slabbed side of the center-point.

GIRARD CARL ROBINSON.
